UNITED STATES PATENT OFFICE.

AUGUST O. BERG, OF LOS ANGELES, CALIFORNIA.

ROCKING-HORSE TOY.

Application filed May 10, 1926. Serial No. 107,965.

My invention is a rocking horse toy mounted on wheels so that it may be drawn along the ground and in such movement the horse will rock.

5 An object of my invention is the construction of a simple toy suitable for children, simulating a galloping horse mounted on a wagon structure so that the device may be drawn along the ground and the 10 horse rock in such operation.

A more detailed object of my invention is to have the action of the wheels rock the horse by utilizing the legs as a pitman or connecting rod between the crank axles and 15 the body of the horse.

In another construction I have one pair 20 of wheels positively actuate the horse to drive same and utilize a free oscillating crank to simulate the movements of the front or other legs of the horse. In this structure the wagon device may be steered by swivelling the front wheels.

My invention will be more readily understood from the following description and 25 drawings, in which;

Figure 1 is a side elevation of one form 30 of my toy, showing both the front and back wheels actuated by cranks connected to the wheels:

Fig. 2 is a front elevation of Fig. 1;

Fig. 3 is a side elevation of a modified form, illustrating the hind wheels as being 35 positively driven and the front wheels oscillating;

Fig. 4 is a front view taken in the direction of the arrow 4 of Fig. 3;

Fig. 5 is a bottom view of Fig. 3, taken in the direction of the arrow 5.

Referring first to the construction of Figs. 40 1 and 2, a suitable platform 1 has braces 2 in which are mounted cranks 3 having wheels 4 thereon. Either one or both of the wheels of each set are rigidly connected to the crank. A stanchion 5 extends up-

45 wardly from the platform 1 and supports a rocking horse designated generally by the numeral 6, this being pivoted on a pintle bolt 7. The body of the horse is designated by the numeral 8, having front legs 9 and

50 hind legs 10. Each of these pairs of legs are provided with pivot pins 11 securing the legs to the body of the horse, the foot of the legs being connected to the crank axles. There may be utilized a suitable cord such as 12 to draw the device.

The toy of Figs. 1 and 2 is intended for

a simple type and a small toy to be made cheaply, and hence is not provided with steering wheels. The device will be of light weight and in order to turn a corner the 60 child will merely pull the front wheels sideways. This device however, may be made of sufficient size for a child to ride on if desired. The front and back wheels will slip one pair relative to the other so that the 65 cranks will be maintained in substantially their correct position to give the horse a rocking movement due to the rotation of the wheels.

In the construction of Figs. 3, 4 and 5, 70 the platform is provided with a swivelled front axle 13, this having a king pin 14 so that the device may be steered. The back wheel construction and the connection of the hind legs to the rear axle is substantially the 75 same as described in connection with Figs. 1 and 2. In this construction however, there is a downwardly depending bracket 15 secured to the platform, this having an oscillating crank 16 journaled therein to which 80 the foot ends of the front legs 9 are connected.

The front axle 13 may have a steering cord, such as the cord 17, attached thereto by nails or eyelets 18. This cord is shown 85 leading over the horse's neck and may be grasped by a child to steer the wheels or by pulling the cord forward over the horse's head the child may pull the toy and at the same time steer the wheels and turn the 90 corners.

The rocking horse of Figs. 3, 4 and 5 is intended to allow a child to ride on the horse. It will be seen that when this is drawn along the ground that the hind legs 95 cause a rocking of the horse on the stanchion 5 and that the front legs will have an oscillating up and down movement simulating to a certain extent that of the hind legs.

In this type of construction the child may 100 rock the horse by throwing its weight backwardly and forwardly and hence by means of the hind legs actuate the rear wheels and drive the vehicle structure forwardly.

It will be seen by the above description 105 that I have provided a toy which for a simple device closely simulates the action of a galloping horse and is such as to appeal to children either as a simple toy to be drawn along the ground or as a larger toy on which 110 a child may ride.

It is manifest that the design may be con-

siderably changed in general construction and in specific details to suit different types of mounting and a different type of toy. Such changes, however, would be within the spirit of my invention as set forth in the description, drawings and claims.

Having described my invention, what I claim is:

1. A rocking horse toy comprising in combination a vehicle-like structure having a pair of wheels with a crank connected to said wheels, a horse-like body structure pivotally mounted to oscillate, a pair of legs connected between the horse body and the crank, a second pair of legs pivotally connected to the horse body, and means to oscillate said legs.
2. A rocking horse toy comprising in combination a vehicle structure having a pair of wheels with a crank forming the axle, a horse-like body structure pivotally mounted on the vehicle, a pair of legs pivoted to the

horse body and connected to the crank, a second crank having a pivotal connection to a device connected to the vehicle, and a second pair of legs pivotally connected to the horse body and connected to the oscillating crank.

3. A rocking horse toy comprising in combination a vehicle structure having rear wheels with an axle in the form of a crank, a pair of front steering wheels, a stanchion, a rocking horse body pivoted to the stanchion, a pair of hind legs pivoted to the body and connected to the crank, a bracket depending from the platform, an oscillating crank connected thereto, front legs pivoted to the horse body and connected to the oscillating crank, and front steering wheels operatively connected to the platform.

In testimony whereof I have signed my name to this specification.

AUGUST O. BERG.
